MUFFLER

Virgil Oldberg, Detroit, Mich., assignor to Oldberg Manufacturing Company, Detroit, Mich., a corporation of Michigan

Application July 2, 1931, Serial No. 548,380

1 Claim. (Cl. 137—160)

This invention relates to mufflers and more particularly to automobile engine mufflers of the thru type.

Mufflers of the thru type, as generally constructed, include an outer shell having headers which are connected by and thru which passes an inner shell, the latter being entirely free of baffles etc. and being provided with perforations, between the headers, leading into the annular space between the shells. Mufflers of this type are advantageous in that they are free from back pressure, and if suitable means between the shells be provided to absorb or neutralize sounds arising within the mufflers, the muffler is found to be highly efficient as a means for eliminating noises which occur in engine operation.

An object of the invention, therefore, is a muffler of the thru type provided with means in the annular space between the shells, to neutralize sounds. More particularly, the invention aims to provide resonance chambers in the space between the shells, as contrasted with mufflers, such as have previously been provided, and which include sound absorbing media disposed between the shells.

A still further object is a muffler of the character above described which is provided with a baffle at its end to prevent flames from passing out of the muffler.

A still further object is a muffler having transverse diaphragms between the shells, the diaphragms being formed of ribs rolled inwardly or outwardly from one or more of the shells, as desired.

Still further objects will readily occur to those skilled in the art upon reference to the following description and the accompanying drawings in which

Figs. 1-4 are longitudinal section views of various forms of mufflers.

Fig. 5 is a section on the line 5—5 of Fig. 3.

Fig. 6 is a partial section view of another form of muffler.

Figs. 7 to 9 show still other forms of mufflers, in section.

Referring to the drawings and more particularly to Fig. 1 it will be seen that the muffler of this form includes an outer imperforate shell 10 provided with end headers 12 and 13 which are connected by an inner shell 14 passing thru both of the headers. In the annular space between the shells are diaphragms 16 and 18 which reinforce the muffler and also form resonating chambers, indicated at R. A plurality of small, closely spaced perforations 19 in the shell 14 afford com-

munication between the interior of the shell 14 and the resonating chambers.

It will be seen that the gases from the engine pass thru the inner shell 14 without obstruction and that sounds within the muffler are attenuated by resonance within the accurately and suitably located resonating chambers R, the fluid within such chambers acting upon the diaphragms 16 and 18.

In Fig. 2 there is disclosed a muffler including an outer shell 20 having headers 21 thru which pass and connecting which is an inner shell 22. An intermediate shell 23 also connects the headers and in the two annular spaces between the shells are diaphragms 24 and 25. The inner shell 22 is provided with closely spaced minute perforations 26 which open into the resonating chambers between the diaphragms 25 substantially as disclosed.

It will be observed that the diaphragms 24 have very little value as resonating diaphragms but are provided to reinforce the muffler, whereas diaphragms 25, besides reinforcing the muffler, serve as true resonating diaphragms.

In Figs. 3 and 5, there is disclosed a muffler which has proven to be very efficient. The muffler of this form includes an outer shell 30 provided with end headers 31, each of which is provided with a nipple 32. Within the shell 30 and spaced from the end headers, are auxiliary headers 33, these being connected by the inner shell 34 and the intermediate shell 35. The inner shell 34 is provided with minute perforations 36, opening into the space between the inner shells 34 and 35 which is filled with a sound absorbing media 37, such as steel wool, mineral wool, or loosely packed fiber or the like. The space between the shells 30 and 35 contains two accurately located resonating diaphragms 38 which form resonating chambers R, communicating with the spaces between the headers 31 and 33 thru slots 39 in the outermost portions of the headers 33.

It will be seen that in this form the gases pass from one nipple 32 to the other without interference, there being no baffles in the path of flow of the gases. Certain of the gases, however, pass from the spaces between the headers 31 and 33, thru the slots 39 and into the resonating chambers R, to provide a medium for resonating vibrations in these chambers.

The form of Fig. 4, is very much like the form of Fig. 3, except that the sound absorbing media 37 is replaced by a plurality of resonating diaphragms 37a which form supplemental resonat-

ing chambers R₁ communicating with the inner shell 34 thru the perforations 36.

In Fig. 6 there is shown a muffler which is very much like those disclosed in Figs. 3 and 4 except that in the space between the slotted header 41 and the end header 42 a conical perforated baffle 43 is disposed, the baffle opening towards the exit nipple 44. A baffle of this character serves the useful purpose of preventing flames which might be present in the muffler from passing out thru the nipple 44.

In Fig. 7 there is disclosed a muffler which is very much like the muffler of Fig. 2, except that the diaphragms in the space between the inner shell 50 and the intermediate shell 51 are formed by roller annular ribs 52 integral with the inner shell and projecting outwardly therefrom and into engagement with the intermediate shell 51 forming resonating chambers R similar to those disclosed in Fig. 1. Resonating chambers of a trapezoidal cross section have proven to be very efficient, much more so than resonating chambers of the rectangular cross section of Fig. 2.

In Fig. 8 there is disclosed a muffler which is more or less like the muffler of Fig. 7 except that the partitions between the inner shell 60 and the intermediate shell 61 are formed by rolled annular ribs 62 projecting inwardly from the intermediate shell and engaging the wall of the inner shell to form resonating chambers R of trapezoidal cross section.

Fig. 9 discloses a muffler which is also very much like the form of Fig. 7 except that the diaphragms between the inner shell 70 and the intermediate shell 71 comprise annular ribs 72 rolled outwardly from the inner shell and annular ribs 73 rolled inwardly from the intermediate shell.

diate shell. These ribs engage one another and are secured to one another to form transverse partitions to form resonating chambers R which, as disclosed, have a lozenge shaped cross section having all of the advantages of the trapezoidal cross section resonating chambers disclosed in Figs. 7 and 8.

Now having described the invention and the preferred embodiment thereof, it is to be understood that the said invention is to be limited, not to the specific details herein set forth, but only by the scope of the claim which follows:

What I claim is:

A through type silencer comprising an outer shell, and headers therefor, inlet and outlet pipes connected to the end headers, intermediate headers spaced from and between the end headers to provide end chambers outside of the intermediate headers, two relatively nested shells within the outer shell and connecting the intermediate headers, the inner shell providing a central through passage connecting the end chambers, sound wave attenuating means in the annular space between the inner shell and the intermediate shell, this space being in communication with the through passage, one or more annular diaphragms between the intermediate headers in the space between the intermediate shell and the outer shell to cooperate with the last mentioned shells to form two or more sound wave attenuating chambers in this space, the intermediate headers being apertured to provide communication between these chambers and the end chambers, the remainder of the attenuating chambers being substantially completely closed.

VIRGIL OLDBERG.
